UNITED STATES PATENT OFFICE.

JAMES T. SARGENT, OF MERCHANTVILLE, NEW JERSEY.

WASHBOARD.

1,152,766.

Specification of Letters Patent.

Patented Sept. 7, 1915.

Application filed August 12, 1914. Serial No. 856,378.

To all whom it may concern:

Be it known that I, JAMES T. SARGENT, residing at Merchantville, in the county of Camden and State of New Jersey, a citizen 5 of the United States, have invented or discovered certain new and useful Improvements in Washboards, of which improvements the following is a specification.

The invention described herein relates to 10 improvements in the parts of washboards employed for supporting the soap. It is the general practice to provide for supporting the soap immediately above the rubbing surface so that the cake is subjected to melting and washing away by water splashed up during the use of the board, as well as to superficial softening when dipped in water prior to being rubbed on the clothes. In order to prevent the softening due to 15 resting in the water held by the soap receptacle provision has been made for the escape of water draining off from the soap and splashed in the soap box during the rubbing. In some constructions the water escapes through a slit to the rear side of the board, and in other forms, the water flows from the soap support down onto the rubbing face. But it is characteristic of both 20 forms that no provision is made for the escape of water from under the cake while resting on its support. And it is also characteristic of former constructions where the discharge is to the front of the rubbing face, that the drainage is distributed all 25 along the upper end of the rubbing face. As the rubbing is principally up and down the middle of the rubbing face, the drainage which carries considerable quantities of soap, running down adjacent to the lateral 30 edges of the rubbing face, is not utilized.

The invention described herein has for its object a construction of the ledge or support on which the under edge of the soap rests, that the supporting area is reduced 35 to a minimum, so that water will escape from the under edge of the cake thus preventing the softening and deliquescent of the under surface of the cake.

It is a further object of the invention to 40 provide for the discharge of the drainage at a point above the portion of the rubbing surface where the principal rubbing is effected.

The invention is hereinafter more fully 45 described and claimed.

In the accompanying drawings forming

a part of this specification, Figure 1 is a front elevation of a form of washboard embodying my improvement; Fig. 2 is a transverse section on a plane indicated by the line II—II Fig. 1; Figs. 3 and 4 are vertical sections on planes indicated respectively by the lines III—III and IV—IV Fig. 1; Fig. 5 is a front elevation of a washboard having applied thereto a different embodiment of my improvement, and Fig. 6 is a vertical section of the same.

In the practice of my invention the washboard as regards its rubbing face 1, side-bars 2, cross-bars 3 and head 4, may be constructed in the usual or any suitable manner. In the construction shown in Figs. 1 to 4, the brand board 5 is formed of sheet metal and has its side and top edges supported in saw kerfs in the side-bars 2 and head-piece 4. The lower portion of the metal sheet is bent to form a ledge 6 projecting to the plane of the front-face of the cross-bar 3. The shell is again bent so that the portion below the ledge will extend down in front of the cross-bar as shown in Fig. 4, and the lower edge of this curtain portion 7 is bent rearwardly to form a flange 8, which projects in under a shoulder on the cross-bar and is held in place by the upper edge of the back-board 9 and cross-bars 3.

By reference to Figs. 1, 3 and 4 it will be seen that the upper surface of the ledge 6 inclines downwardly from its ends and preferably connects at their lowest points with a common spout 10 which extends downwardly from the rear edge of the ledge to a point above the middle of the rubbing face. By reason of this construction all water falling onto the ledge will flow toward this spout and then down into the rubbing surface. It is preferred that the ledge should be provided with a gutter *a* so that drainage may flow under the cake toward the spout. While this gutter may be formed in any suitable manner, it is conveniently formed in the construction shown in Figs. 1 to 4, by giving the ledge an upward inclination from its rear side, so that when a cake rests on the higher front edge *b* of the ledge or supporting part or member and its rear side against the back support, which in this case is the brand board, there will be a clear passage or gutter underneath the cake to the spout.

It is preferred that the rear support for the cake as for example the brand board 5,

should be provided with projections of small areas such as ribs 11, so that water may escape freely between the cake and the rear support.

5 It is characteristic of my improvement that the under and back supports of the soap as the front edge *b* of the ledge and the tops of the ribs 11 are of very small areas compared with the areas of the edge 10 and side of the cake, and therefore water will drain rapidly away.

It will be understood that my improvements which pertain to the parts serving to support the soap are not dependent upon 15 any particular form, construction or arrangement of adjacent parts of the washboard. As for example in Figs. 5 and 6 the under support 6^a for the soap is carried by a metal sheet 12 wholly independent of the 20 brand board 13. The under support for the cake can be arranged and held in any convenient manner above the rubbing surface.

I claim herein as my invention:

25 1. A washboard having a soap support with its upper or supporting surface inclined transversely of the rubbing surface for conducting away water draining from the soap in combination with means for 30 directing such drainage onto the rubbing surface in use.

35 2. A washboard having in combination therewith a soap support provided with a gutter permitting the flow of water from below the cake resting on such support down onto the rubbing face in use, said gutter being inclined transversely of the rubbing face, and means for directing water from the gutter onto the rubbing face.

40 3. A washboard having in combination therewith a support for the soap having portions of its upper surface upwardly and outwardly inclined toward its ends whereby

water may be directed from the sides of the board toward the median line of and onto 45 the rubbing face in use.

4. A washboard having in combination therewith a soap support having portions of its upper surface inclined upwardly but in opposite directions from a common point 50 above the middle portion of the rubbing face in use, whereby the drainage is delivered to the middle portion of the rubbing surface.

5. A washboard having in combination 55 therewith a soap support having portions of its upper surface upwardly and oppositely inclined from a common point and provided with a spout arranged at the intersection of the inclined surfaces for the reception of 60 water flowing down such surfaces and adapted to discharge such water onto the rubbing face in use.

6. A washboard having in combination therewith under and rear supports for the 65 soap constructed to permit the flow of water between the side and edges of the cake and such supporting parts, the under support being inclined transversely of the rubbing face and provided with a spout for directing 70 the water onto the rubbing face in use.

7. A washboard having in combination therewith a soap support inclined transversely of the rubbing face and provided with a spout arranged above and in approximate alinement with the median line of the rubbing surface whereby the soapy water draining from the soap is discharged where the greatest amount of rubbing is effected. 75

In testimony whereof, I have hereunto set 80 my hand.

JAMES T. SARGENT.
